J. E. PHILLIPS.
GUARD FOR POWER PRESSES.
APPLICATION FILED JUNE 28, 1921.

Patented June 6, 1922.

UNITED STATES PATENT OFFICE.

JOHN EDWIN PHILLIPS, OF BIRMINGHAM, ENGLAND.

GUARD FOR POWER PRESSES.

1,418,327.

Specification of Letters Patent. Patented June 6, 1922.

Application filed June 28, 1921. Serial No. 481,015.

To all whom it may concern:

Be it known that I, JOHN EDWIN PHILLIPS, a subject of the King of Great Britain, residing at Birmingham, England, have invented certain new and useful Improvements 5 in Guards for Power Presses, of which the following is a specification.

This invention relates to guards for power 10 presses, and particularly to guards of that type comprising a collapsible lazy-tong frame or frames adapted to be extended during the down or working stroke of the press plunger and prevent injury to the hand of the operator.

15 It has already been proposed in guards of the above type automatically to effect both the collapsing and extending of the lazy-tong frames by a moving part of the press, such as the press plunger, but according to 20 the present invention the guard frame or frames are only extended by a moving part of the press, it being proposed to effect the collapsing of the frame or frames by means of a spring. The guard frame or frames 25 are preferably extended by means of a Bowden wire connected either to the press plunger or to some other moving part of the press. No such arrangement has hitherto been proposed.

30 Figure 1 represents an elevational view showing an arrangement in which the guard is operated by a Bowden wire, the latter being actuated by a lever against which a part upon the press plunger strikes. Two 35 guard frames are shown, but if desired a single frame only may be employed.

Figure 2 shows an alternative method of operating the Bowden wire, the latter being actuated by a cam upon the crank shaft of 40 the press.

Figure 3 is a cross-section on the line x^2 of Figure 2.

The same reference numerals indicate corresponding parts in each of the figures.

45 Referring to the drawings, the guard comprises two lazy-tong frames 1 mounted upon the axial rod 5, and connected at their upper inner ends to a sliding sleeve, the guard frames being automatically collapsed by the 50 coiled spring 9. The one end of the Bowden-wire 29 is attached to the front plate 19 carried by an integral collar upon the upper end of the sleeve member, the respective end of the outer casing 30 of the 55 wire being arranged to abut against a fixed stop 31 through which the wire passes, the

said stop being preferably carried by the bracket upon the bed of the press, as shown. The opposite end of the wire 29 passes axially through an adjusting screw 32 carried by a fixed arm or bracket 33 upon the press frame 34, at one side of the plunger, the extremities of the wire being fixed to the outer end of a lever 35 pivoted at 36 to the upwardly cranked inner end of the 60 bracket 33. The respective end of the casing 30 of the wire is arranged to abut against the head of the adjusting screw 32, as shown. The lever 35 is arranged normally in a substantially horizontal position, and carries a 70 roller 37 at its inner end which is adapted to be engaged by a block or striker 38 fixed upon the plunger 39 of the press. The arrangement is such that on the down stroke of the plunger 39 the block or striker 38 75 strikes against the roller 37 upon the lever 35 and forces the said end downwards, so that the opposite end of the lever 35 which is connected to the end of the Bowden wire 29 is raised. The wire 29 is thus drawn 80 through its casing 30, its opposite end moving the plate 19 to which it is attached downwards, so that the integral collar carrying the said plate, actuates upon the upper inner ends of the frames 1, the ends of the latter 85 moving down upon the vertical rod 5, so that the spring 9 upon the said rod is compressed and the guard frames 1 extended. During the upward stroke of the press plunger the block or striker 38 upon the latter is moved 90 out of engagement with the roller 37 upon the lever 35 so that the latter assumes its original position, and the guard frames 1 are automatically collapsed by the coiled 95 spring 9.

Referring to the modification shown in Figures 2 and 3, instead of the lever 35 operating the Bowden wire 29 being actuated by means of a member upon the press plunger, as above described, it may be actuated by means of a suitably shaped cam 40 upon the crank shaft 41 of the press, the cam 40 being arranged to engage with the roller 37 upon the said lever in such a manner as to operate the wire 29 and effect the 105 extending of the guard frames during the down stroke of the plunger. The bracket 33 to which the lever 35 is pivoted may be carried by a fixed bearing or support.

If desired the Bowden wire may be operated by any other suitable moving part of the press, whilst an ordinary wire or cable

may be employed if desired, the wire being arranged to pass over suitable pulleys or through guides.

The guard may either consist of a single lazy-tong frame or of a pair of frames, as desired.

Having fully described my invention, what I desire to claim and secure by Letters Patent is:—

- 10 1. A press-guard comprising a collapsible and extensible frame, a cable operatively connected at one end to the said frame, a lever connected to the opposite end of the cable and operated by a moving part of the press, and a coiled spring for automatically collapsing the guard on the return stroke of the plunger.
- 15 2. A press-guard comprising a collapsible and extensible frame, a cable operatively connected at one end to the said frame, a lever connected to the opposite end of the cable and operated by a moving part of the press, and a coiled spring for automatically collapsing the guard on the return stroke of the plunger.
- 20 3. A press-guard comprising a collapsible and extensible frame, a cable operatively connected at one end to the said frame, a lever connected to the opposite end of the cable and operated by a moving part of the press, and a coiled spring for automatically collapsing the guard on the return stroke of the plunger.

3. A press-guard comprising a collapsible and extensible frame, a cable operatively connected at one end to the said frame, a lever connected to the opposite end of the cable, a cam operating the said lever and actuated by the crank shaft of the press, and a coiled spring for automatically collapsing the guard on the return stroke of the plunger.

3. A press-guard comprising a collapsible and extensible frame, a cable operatively connected at one end to the said frame, a lever connected to the opposite end of the cable, a cam operating the said lever and actuated by the crank shaft of the press, and a coiled spring for automatically collapsing the guard on the return stroke of the plunger.

In testimony whereof I have hereunto set my hand in presence of two subscribing witnesses.

JOHN EDWIN PHILLIPS.
